UNITED STATES PATENT OFFICE.

CLIFTON F. LEATHERBEE, OF NEWTON, MASSACHUSETTS, ASSIGNOR TO PAINTING MACHINE COMPANY, OF KITTERY, MAINE, A CORPORATION OF MAINE.

WOOD-TREATING MACHINE.

1,107,623.

Specification of Letters Patent. Patented Aug. 18, 1914.

Application filed April 4, 1910. Serial No. 553,830.

To all whom it may concern:

Be it known that I, CLIFTON F. LEATHERBEE, a citizen of the United States, residing at Newton, in the county of Middlesex and 5 State of Massachusetts, have invented certain new and useful Improvements in Wood-Treating Machines, of which the following is a specification.

The present invention relates to machines 10 for applying liquids and fluids of various kinds to the surfaces of materials of various contours, and more especially to apparatus which may be used to dry lengths of flooring, strips of molding, cross arms, and 15 like strips or lengths of material which have been subjected to the application of paint, stain, varnish, creosote and other finishing or preservative substances.

The principal objects of my present invention are the provision of a machine characterized as above noted which is adapted to receive and dry the treated material speedily and to provide improved means for removing the treated material from the machine 25 and keeping it exposed to the atmosphere for a certain period of time to the end that it may dry and be more readily handled, as well as certain further objects herein-after more fully to appear.

30 In the attainment of the objects above set forth, together with additional advantages to be disclosed below, I have provided a construction, a preferred embodiment of which is illustrated in the accompanying drawings wherein:—

Figure 1 is a side elevational view, partly in section, illustrating the feeding fluid applying and polishing mechanism; Fig. 2 is a plan view of the machine shown in Fig. 1; 40 Fig. 3 is a sectional view taken on the line III—III of Fig. 2; Fig. 4 is a plan view of the preferred form of conveying and elevating mechanism utilized by me in connection with the machine of Figs. 1 to 3; Fig. 5 is 45 an end elevational view of a portion of the apparatus of Fig. 4, part of such apparatus having been removed and part shown in section taken on the line VII—VII of Fig. 4; Fig. 6 is an enlarged view similar to Fig. 5, showing certain details of the operating parts on an enlarged scale; Figs. 7 and 8 are further enlarged detailed views of certain elements of the device of Figs. 4, 5 and 6; Fig. 9 is a side elevational view taken on the line 55 XI—XI of Fig. 6; Figs. 10, 11 and 12 are detailed views of the device of Figs. 8 and

9, Fig. 12 being taken on the line XIV—XIV of Fig. 11.

Referring now more particularly to Figs. 1 to 3, it will be noted that in carrying out 60 my invention I make use of a framing 20, preferably of cast metal provided at each end with supports 20', which may be conveniently located adjacent to the end of a planer or other machine for forming flooring, wainscoting and similar products. At 65 the delivery end of the machine, I provide a primary belt conveyer 21 longitudinally disposed with relation thereto for removing the treated material discharged therefrom and in alinement with but on a plane below 70 the conveyer 21, for a purpose to be below described, a secondary belt conveyer 22 for receiving and delivering such articles.

In order that the increase of cost and loss 75 of time incident to rehandling the material after leaving the planer, may be saved and to insure a direct feed of such material through the machine without lateral displacement, it may be fed by the live rolls of 80 the planer; otherwise such feed may be effected by the oppositely disposed live rolls 23 and 24 driven from the motor 25 through the gearing to be hereinafter described. A stationary guide block 26 and a spring guide 85 27 disposed oppositely thereto and cooperating therewith are located closely adjacent the rolls 23 and 24 to insure the alinement 90 of the material as it is fed through the machine. A roll 28 is provided for the initial support of the fed material, and as it passes the rolls 23 and 24 it is successively engaged 95 by the single idler roll 30, and the pairs of live rolls 31, 32, and 33, 34 adapted to hold it in contact with the brush devices 35, 36, 37 and 38, designed respectively for applying 100 the liquid, for rubbing it in, for wiping any excess from the edges of the materials and for removing any vestiges from the face thereof.

On viewing Fig. 1 particularly it will be observed that I mount in the framing 20 the rotatable brush 35, movable vertically to the end that compensation may be made for wear in service by means of its suspension in 105 the outer ends of the yoke 40 pivoted in the casing as indicated at 41, 41, one of which is provided with an adjusting screw 42.

For the purpose of furnishing a supply 110 of treating liquid to the brush 35, I make use of a pump 45 to lift the liquid from the supply tank 46 by the pipes 47 and 48 lead-

ing from such tank and venting just above the spreader plate 50 pivoted at 51 to a transverse septum 52 in the framing and held in contact with the brush 35 by means 5 of an adjusting screw 53 threaded into an enlarged portion of the framing at the angle 54, whereby wear of the brush may be further compensated for. The floor 55 of the framing forms a drip pan for the several 0 brushes and a drain pipe 56 continuously open to the tank 46 is provided to convey thereto any excess liquid that may perchance fall upon such pan.

For driving the pump 45, the brush 35, and 5 the rolls 24, 32 and 34, in unison, to the end that a uniform application of liquid may be had, I mount on the shaft of the motor 25 a pulley 60 driving by means of a belt 61 the pulley wheel 62 which is mounted on the 0 shaft 63 carrying the roll 34. The opposite end of the shaft 63 is provided with a gear 65 which by means of a chain 66 drives the gear 67 mounted on the shaft 68 of the roll 32. The shaft 68 carries on the end, (opposite to that carrying the gears 67 and 69), 5 a gear 73 driving, by means of the intermediate gears 74 on a shaft 74^a, and 75 on the shaft 76, the gear 75^a on the shaft 76^a carrying the roll 31. At the end of said shaft 0 76 is mounted a sprocket wheel 77 driving by means of the chain 78 the pump 45. On the end of the shaft 72 opposite the sprocket 71 is carried a gear 79 which through intermediate gears 80 on the shaft 80^a, and 81 on 5 the shaft 82 drives the gear 82^a on the shaft 83^a, carrying the roll 23. Upon said shaft 82 is mounted a pinion 83 driving through the chain 84 the sprocket 85 on the shaft 86 carrying the brush 35.

0 In order that the upper rolls 23, 30, 31 and 33 may be adjusted axially to accommodate materials of differing thicknesses, and that they may be conveniently removed where desirable, I preferably mount them in 5 the opposing members of pairs of boxes 88, 89, 90 and 91 pivoted to opposite sides of the framing 20, each box being provided at its free end with an adjustable screw device 92 having engagement with an extension of the 0 box and inserted in a socket formed in the framing. Springs 92^a—92^b under a certain degree of compression are mounted upon the said screw devices 92 on both sides of said extension in order to compensate for 5 any slight unevennesses in the material.

Inasmuch as I have designed the machine illustrated as an embodiment of my present invention primarily for the purpose of applying a highly volatile treating 0 compound to flooring, the respective sizes of the pulley 77 and 77^a by which the pump is driven through the belt 78, should be so proportioned that as closely as possible the precise amount of liquid that may be taken 5 up by the brush 35 be delivered upon the

spreader plate 50, in order to avoid any accumulation upon the drip pan 55 or the rolls. As a further precaution against spattering of the liquid, or throwing thereof from the brush 35, I provide such brush 70 with a cover 35^a, open at the top, and supported by the shaft 86 and yoke 40. This is especially desirable since my improved machine is used with great economy for the treatment of flooring as it issues from the 75 planer, and such locations usually present a considerable amount of dust, chips, shavings and other highly inflammable substances.

To insure that the liquid as it is ejected 80 from the pipe 48 be distributed evenly over the spreader plate 50, I mount on the open end of the pipe a striking plate 48^a which also serves the further purpose of preventing any spattering of the fluid on the brush 85 35 or the framing 20 and thus prevents accumulation thereon of the heavier residual held in suspension in the volatile fluid of such paint. As a further guard against accumulation of residual material, I provide 90 the rolls 30, 31, and 33 with shields 30^a, 31^a and 33^a.

Each of the stationary brush devices 36 and 38 is vertically adjustable by means respectively of the screw devices 95, 96 threaded into a bottom extension of the framing 20, to the end that compensation may be had for any wear of such brushes in service, and each of the brushes 37, 37 is adjustable laterally by the screw members 97, 97 100 threaded into the sides of the framing 20 and resting at their inner ends in the stop blocks 98, carried upon a plate 99^a supported by the angle bars 99, 99, also mounted in the framing 20, for the purpose of limiting 105 the inward movement of the said brushes 37.

For a three-fold purpose, viz., alining the material in its passage through the machine, directing it between the two brushes 37, and holding it in contact with the brush 36 110 (here shown as made in three parts carried in a frame for the sake of convenience in replacement and in order that unequal wear of the several parts may be cared for without discarding unworn portions) I provide the 115 coöperating spring device comprising the laterally pressing, oppositely disposed springs 100, 100 adjustably mounted in blocks 101, 101 carried by the yoke 102, and the downwardly pressing spring 103 in the 120 block 104, provided upon said yoke 102 between the springs 100.

Referring now more particularly to Figs. 4 to 12, it will be observed that as the treated material issues from between the 125 rolls 33 and 34, it is deposited on one end of the belt conveyer 21 and thence discharged upon the secondary belt conveyer 22, disposed on a lower plane to the end that delivery of material from the machine upon 130

the conveyer 21 may not interfere with the action of the device by means of which the attendant of the machine of Figs. 1-3 removes the material for drying from the conveyer 22 to the apparatus below to be described. The belt 22 is provided at intervals with cleats 22', preferably of inverted V-shape, disposed transversely thereof, for the purposes of preventing contact of the 10 treated surface of the material with such belt and consequent marring of such treated surface or soiling of the belt or both, and to provide ways upon which the removing device may slide freely. The removing device, as may be clearly seen in Figs. 4 and 5, comprises in preferred form a fulcrumed hand lever 110 carrying pivotally mounted thereon an actuating rod 111 which has attached thereto a connecting bar 112 to which are pivotally mounted the outer ends 113, 113 of a plurality of rocking levers 114, 114, the opposite ends 115, 115 of which levers are attached to a strip 116 disposed longitudinally of the conveyer belt 22 20 and adapted to be moved transversely thereof in order to remove from such belt the material and deposit it upon the angularly disposed guideways 117 from which it is taken up for drying by means of the elevating and lowering mechanism proper now to be described.

From the guides 117 the material passes on to one of the sets of fingers 118 provided at intervals on the longitudinal members 119 (here shown as pipes) supported at each end upon links of the endless chains 120, 120 engaging sprockets 121 and 122 (Fig. 6). One of the upper sprockets 121 is driven intermittently, in a manner to be hereafter more fully described, from a shaft 123 which has suitable clutch driving connections to the hub of the sprocket 124 and driven from the motor 25 through a sprocket 124^a mounted on said shaft 123, a pair of sprockets 63^b 40 and 63^c on the shaft 63^d, and a sprocket 63^a on the shaft 63^e, chains 64^a and 64^b connecting said several sprockets and driving the two conveyers in unison. The sprocket 124 is adapted to drive by means of the chain 50 125, a sprocket 126 carried on the shaft 127, which in turn by means of a worm 128 drives a gear 129 keyed on the shaft 130 which carries the sprocket 121.

It will be apparent from an inspection 55 of Figs. 7 and 8, the pipes 119 are mounted against rotation relative to the chain 120 by flattening them and riveting them to the extended wings 131, 131 provided on the alternate links of the chain 120.

As is clearly to be seen on viewing Figs. 5 and 6, there is disposed opposite to each of the fingers 118, a finger 132 provided with a bent portion 133, the purpose of such construction being that as the material is turned, during the progress of the elevating

mechanism in the direction indicated by the arrow (Fig. 5), and thence drops away from contact with the fingers 118, it is restrained by the fingers 132 from falling or disengagement from the chain until in its descent it comes in contact with the guides 134 and is thence discharged onto the floor.

By virtue of the step by step movement in the travel of the material and the manner of discharge herein described, when quick-drying liquids are used in treating it, such material has an opportunity to become thoroughly dried by the time it is discharged upon the guides 134 and thence upon the floor 135; also that it is so discharged with the unpainted side down and is then ready to be moved away for shipment or storage without danger of rubbing of the painted portion. Moreover, if the treated surface rested upon the fingers 118 during the whole of the travel, those portions contacting with such fingers would not have an opportunity to become as thoroughly dried as the portions exposed to the atmosphere.

As a means for giving a step by step movement to the elevating mechanism shown in plan Fig. 4 and side elevation Fig. 5, that is, allowing it to move only the distance between two of the series of fingers 118, on a single impulse, I have provided the mechanism which is shown in plan in Fig. 4, in side elevation in Fig. 5, in enlarged detail in Figs. 6 and 9 to 12. From an inspection of the figures it is observable that for throwing the mechanism into and out of action I make use of a rocking lever 140 pivoted upon the actuating rod 111, at one end as indicated at 141, and at the other end as indicated at 142, to the clutch actuating rod 143 which terminates in a bifurcated portion 144 engaging the grooved collar 145 on the shaft 123. Actuation of the rod 111 in the direction indicated by the arrow (Fig. 4) moves the rod 143 in the direction indicated by the arrow (Fig. 6), forces the collar 145 to the right against the cone 147, mounted in a yoke 146, moving the face 147^a of the cone into contact with the lever 148 which in turn operates the cam 149 adapted to tighten the spring collar 150 upon the hub of the sprocket 124. As this collar is fixed against rotation relatively to the shaft 123, the actuation just described causes the shaft 123 to drive the sprocket 124. For the purpose of allowing a ready automatic opening of the clutch by simple mechanism, the yoke 146 is in turn pivoted in a yoke 155 pivotally supported at one end 156 in a bracket 157 and carried at the other end in the slotted head 158 of a pivoted supporting member 159, said supporting member being provided with a tripping device 160 pivotally mounted thereupon and having a screw 161 whereby the angularity of the mounting of the tripping device relatively to the supporting

130

lever may be varied and the respective ends of the fingers 118 and of the guides 117 be brought into position and alined to insure the delivery of the material from the guides 5 to the fingers upon actuation of the removing device by the lever 110. To prevent the tripping device from descending to a position where the finger supports 119 would not strike it and throw out the clutch mechanism above described, I provide on the supporting member 159, a stop 162, and to insure the disengagement of the tripping device from such finger support, the pivot point 163 should be so located as to free the 5 end of the device 160, when the clutch is thrown out, and allow the device 160 to descend. From the foregoing description it will be understood that when the actuating rod 111 is moved in the direction indicated 0 by the arrow, the drying mechanism will lift the material resting upon fingers 118 on the supports 119 and continue such movement until one of such finger supports contacts with the tripping device 160, when supporting member 159 will move to the position shown in Fig. 6, the clutch device above described will be thrown out and the drying mechanism remain inactive until the actuating rod 111 is again moved in the direction indicated by the arrow.

It is believed that machines embodying my present inventions, and the mode of operation thereof, will be understood without more amplified or particularized description.

Having thus described my invention and illustrated its use, what I claim as new and desire to secure by Letters Patent is the following:

- 1. In combination with a machine for treating material having means for moving material therethrough, a conveyer positioned relatively to the treating machine for receiving the treated material as it comes from the machine and arranged for lateral discharge, a drying apparatus having means for receiving and sustaining said material as it comes from the conveyer, means for driving said moving means and conveyer in unison, means for removing the treated material from said conveyer to said drying apparatus, and means for actuating said removing means and said drying apparatus simultaneously.
- 2. In combination with a machine for treating moving material, means positioned for receiving the treated material as it comes in one direction from said machine and arranged for discharging such material in another direction to a drying apparatus, and a drying apparatus having primary means for receiving the treated material as it is discharged from said receiving means, second-

ary means for receiving the material as it passes from said primary means, and means 65 for imparting motion to said drying apparatus in synchronism with said receiving and discharging means.

3. In combination with a machine for treating moving material and delivering it 70 treated side down, a drying apparatus having means for receiving and sustaining the treated material as it is discharged from the machine in such position, and thereafter delivering it treated side up, mechanism for 75 driving said machine and apparatus in unison, and means for imparting motion to said driving mechanism.

4. A drying apparatus having a series of fingers for receiving treated material, conveying the same, and reversing the position thereof, a second series of fingers for receiving the material as it passes from said first mentioned fingers and sustaining and delivering it in such reversed position, driving 80 mechanism for said apparatus, and means for imparting motion to said driving mechanism adapted to be actuated through a limited portion of the movement of said drying mechanism.

5. In combination with a machine for treating material having means for moving material therethrough and delivering it substantially horizontally, a substantially vertical drying apparatus for receiving the 95 treated material, means for driving said moving means and drying apparatus in unison or said moving means alone, means for removing the treated material substantially horizontally from said machine to said drying apparatus, and means for controlling the actuation of said driving means whereby a step by step movement is given said drying apparatus without varying the movement of said moving means.

6. In combination with a machine for treating material and delivering it substantially horizontally treated side down, a drying apparatus having means for receiving the treated material as it is discharged from said machine treated side down and thereafter delivering it treated side up, delivery guides between said machine and said receiving means, mechanism adapted to give said apparatus a step by step movement 110 whereby it may receive material from said guides, and means for alining the said guides and receiving means at the end of each movement of the drying apparatus.

In testimony whereof, I have hereunto 120 signed my name in the presence of the two subscribed witnesses.

CLIFTON F. LEATHERBEE.
